METHOD OF MAKING ARTICLES OF
POLYGONAL CROSS-SECTION

Richard Lester Wilcox, Waterbury, Conn., assignor to The Waterbury Farrel Foundry and Machine Company, Waterbury, Conn., a corporation of Connecticut

Application May 15, 1933, Serial No. 671,165

2 Claims. (Cl. 10—27)

This invention relates to new and improved means and method for making articles having a polygonal cross section, particularly bolts and the like.

5 It is the object of this invention, among other things, to produce an article of the character described by the application of successive pressures, some in the direction of the axis of the article and others at substantially a right angle therewith such pressures resulting from the action of mechanisms of simple design that may be adapted for use in a press, header or the like. A further object being to provide means whereby a symbol, such as a trade-mark or 10 the like, may be impressed in one or more of the polygonal faces of the article.

To these, and other ends, this invention consists in the means and method for making articles having a polygonal cross section, having certain details of construction and combinations 20 of parts, as will be hereinafter described and more particularly pointed out in the claims.

25 Referring to the drawings, wherein like characters of reference indicate like parts in the several figures;

Figure 1 is a sectional view of the applicable portion of the mechanism utilized in this invention;

30 Figure 2 is a transverse sectional view of a portion thereof, the parts in section being generally taken upon line 2—2 of Figure 1, the relative parts, however, in this view being different than in Figure 1;

Figure 3 is a fragmentary plan view of the 35 forming die;

Figures 4, 4A, 5, 5A, 6, 6A, 6B, 7 and 7A, inclusive, are views of one form of a blank showing the shapes resulting from the several operations thereon.

40 Figures 8, 8A, 9, 9A, 10, and 10A are illustrations of completed articles;

Figure 11 is a view of a blank, of slightly different shape, and as produced by a pressure operation; and

45 Figure 12 is a perspective view of one of the pressure dies.

Heretofore it has been the usual practice to form the head of an article, such as a bolt or the like, by the application of endwise pressure upon the blank.

50 With this invention the polygonal shape is acquired by pressure applied to the perimeter of the head of the blank, as distinguished from endwise pressure, thereby producing a bolt head of superior quality with faces that have an

attractive finish, and the metal thereof is toughened by its compression in the forming die. Thus, the product is adapted for use under more severe conditions than is possible with bolt heads made under the old process.

5 In the embodiment of the invention, one form of which is illustrated in the drawings, 10 designates the bed as associated with the body 11 of the machine, upon which a die block 12 is secured in any preferred manner. Within this 10 latter is a cut-off die 13, pressure dies 14 and 15, forming dies 16, extruding die 17, and pointing die 18. The opening in the cut-off die 13 is substantially the same shape and size in cross section as the rod 19 from which the blanks 20 15 are cut by the knife 21. The extruding die 17 is enclosed within a die shell 22 and rests upon a backing block 23. The pointing die is enclosed within the shell 24 and upon opposite sides thereof are the guide block 25 and backing 20 block 26.

Opposite the die holder is a punch holder 21, in which is mounted the punches 28, 29, 31 and 32, and punch carrier 30, all of which abut against a backing plate 33. In the punch carrier 25 30 is a pressure pin 34, having a head thereon, and between which and the backing plate 33 is the spring 35.

In practice the die block 12 and its associated parts are held rigid and the punch holder 21 is 30 moved toward and away therefrom in any manner well known in the art. By reason of this motion the punches engage the blanks in line therewith and in conjunction with co-operating dies and other mechanism, perform operations 35 thereon.

When the punch holder 21 is distant from the die block 12, the cut-off portion of the rod (now the blank 20) is transferred into line with the punch 28 and die 14. The thereafter movement 40 of the punch holder 21 toward the die block 12 causes the blank to be projected into the die 14 against the end of the knockout pin 36, which at this time is held in a rigid position. When so positioned, the outer end of the blank 20 projects beyond the face of the die 14 and this portion is subjected to the pressure of the punch 28 45 and is coned substantially as shown in figures 1 and 5. As the punch holder 21 moves away from the die block 12 the knockout pin ejects the 50 blank from the die 14 and suitable transfer mechanism engages and transfers it into line with the punch 29. At the next movement of the punch holder 21 toward the die block 12, the punch 29 engages the blank in line therewith, 55

and projects it into the die 15 until its inner end engages the knockout pin 37 now held in a fixed position. The action of this punch changes the shape of the coned head to one having a diameter considerably larger than that of the distance across the corners of the finished polygonal head, and considerably thinner, a collar being formed on the inner face by the recess in the face of the die 15. With the next movement of the punch holder 27 away from the die block 12, the knockout pin 37 ejects the blank from the die 15, which, through transfer devices is moved to the forming die 16. The latter is constructed with a body member 38 which is held stationary within the die block 12.

Through the body member is an opening 49 of plural diameters, in the walls of the smaller diameter of which are a plurality of radial slots 41. The rear walls of these slots (six in number) are at an angle to the axis of the opening 40, and as the apparatus is shown, are designed to produce an article that is hexagonal in cross section. A greater or less number of faces will correspondingly increase or reduce the number of slots. Movable in each slot is a pressure die 42 which has a flat inner face 43 of substantially the width of each of the faces of the polygonal head, and each of the faces being substantially parallel with the faces of the other pressure dies 42 in the group. On each die opposite its pressure face is a cam face 44, which rides against the angular wall of the slots 41, an inner cam face 45, and a stop shoulder 46.

Movably mounted within the opening 40 and a concentric opening in the bushing 47 is a sleeve 48 having a coned head 49, the angle of inclination of which is substantially the same as that of the cam faces 45, which engage therewith. Surrounding the sleeve 48 and between a collar 50 thereon and the bushing 47, is a coil spring 51, which maintains a constant tension upon the sleeve to move it toward the exposed face of the die block.

Secured to the body member 38 is a plate 52 against which the stop shoulders 46 engage when the pressure dies 42 are in their outer position, that is, preferably with the ends thereof substantially flush with the exposed face of the die block 12.

Within the sleeve 48 is a guide sleeve 53 having a stop shoulder 54, which engages a shoulder within the bore of the sleeve 48 and limits the relative movement thereof in one direction. This position being shown and illustrated in Figure 2, wherein the face of this guide sleeve is substantially flush with the exposed face of the die block 12. Surrounding the sleeve 53 within the bore of the sleeve 48 and between the shoulder 54 and a nut 55, is a spring 56 that is much lighter than the spring 51. Movable within the nut 55 and sleeve 53 is a knockout pin 57.

In Figure 2 the several parts constituting the forming dies, the punch carrier 30, and associated parts are in their relative positions as the blank is presented thereto and still held by the transfer devices.

As the punch holder 27 moves toward the die block 12, the blank is pushed into the sleeve 53 by the pressure pin 34 and the underside of the head thereof engages the end of said sleeve. Further continued movement compresses the relatively light spring 56 until the inner end of the sleeve 53 abuts against the nut 55, at which time the opposite end of the sleeve is substantially flush with the face of the coned head 49

substantially as shown in Figure 1. The head of the blank is now positioned between the pressure faces of the dies 42, and the spring 35 is compressed during the further movement of the punch carrier until the end of the latter engages the outer faces of the die 42. Thereafter, continued movement of the punch carrier 30 imparts movement to the pressure dies 42. These dies under this action move inwardly toward the axis of the blank by reason of the engagement of the cam faces 44 with the walls of the angular radial slots 41. Endwise pressure is also thus applied to the sleeve 48 through the engagement of the cam faces 45 with the coned head 49. During the inward movement of these dies 42, the inner pressure faces 43 are forced against the outer wall of the head of the blank, causing the metal to flow by reason of such pressure until the inward limit of movement of the dies 42 is reached, that is, until the angular walls on each side of the pressure faces contact with each other, thus completely shaping the head.

As pressure is applied by the dies 42 and the metal flows as a result thereof, both in an up and a down direction, this flow is not resisted to any appreciable extent. This results from the receding of the pressure pin 34 into the punch carrier 30, and the free space above the coned head. Such space is provided through the engagement of the cam faces 45 with the coned head 49 which moves the sleeve away from the head of the blank against the tension of the spring 51 faster than the metal flows. As the punch carrier 30 is withdrawn the spring 51 forces the sleeve 48 outwardly, thus moving the pressure dies away from the axis of the blank and out of engagement with the head thereof. At the same time the knockout pin 57 projects the blank out of the guide sleeve 53 which moves outwardly relatively to the sleeve 48 by the tension of the spring 56. When the guide sleeve 53 is in its outer position, determined by the engagement of the collar 50 with the body member, the outer end of the guide sleeve 53 is flush with the exposed face of the die block 12. The transfer mechanism now engages the blank and carries it to the extruding die 17 where it is projected therein by means of the punch 31, after which it is ejected by the knockout pin 59 and presented to the pointing die 18, being projected therein by the punch 32 and ejected therefrom by the knockout pin 58. If the underside of the head is slightly irregular by reason of the application of the pressure dies 42 thereto, this irregularity is eliminated and the face made flat in the next succeeding operation in the extruding die 17, as shown. This results, within the die, from the endwise pressure applied to the head, which will eliminate any irregularities therein.

The inner sleeve 53 provides a convenient means for receiving and guiding the blank into the forming die. It is particularly advantageous for blanks with short shanks, because the outer end thereof is flush with the exposed face of the die block 12, while the coned head 49 is distant therefrom, the open space between the coned head and face of the die block being bridged by the sleeve 53. Thus, there is produced by the means and mechanism described and disclosed, a bolt blank that is produced from a wire rod and the head shaped by lateral pressure, the shank extruded and pointed if desired. The lateral pressure applied by this

process produces the polygonal shaped head without the application of subsequent endwise pressure, as where the head is preliminarily fluted by lateral or other means.

5 With some metals the extent of irregularity on the top and bottom faces of the head is greater than in others and this tendency may be materially counteracted by forming the underside of the head with irregularities, the high points of which will correspond with the natural flow of the metal in the succeeding operation where the tendency to irregularities would be the least and vice versa. To accomplish this, the die 15 is preferably provided with a face 10 that is formed with depressions, substantially as shown at 60 in Figure 6, separated by intermediate high points 61. In Figure 11 is shown a die and blank so formed and as presented to the forming dies. The positions of these high 15 points 61 such that they are substantially opposite the corners of the polygon where there is less tendency to lengthwise flow than at the centers of the flat faces, which are opposite the depressions 61. These depressions are entirely 20 removed in subsequent endwise pressure operations and the metal at the bottom thereof is caused to flow so that it is substantially flush with the high points 62, thus producing a flat 25 as distinguished from an irregular surface.

30 It is desirable in some cases that articles of the character herein referred to should be identified by a symbol, trade-mark or the like, whereby to indicate when and by whom manufactured, or to indicate the character of the 35 material of which the article is made, and for other reasons. Attempts have been made to accomplish this result, by forming the symbol 40 on the top face of the article. This is unsightly and destroys its neat appearance, and if the symbol is raised rather than impressed, it is further objectionable, because it forms an obstruction upon which cloth, waste, or the like, will catch and cling when the articles and adjacent parts are being cleaned. Again in the 45 manufacture of such articles, symbols or marks have been utilized in the process of manufacture to indicate the character of the material of which the article is made. In such cases, these symbols are removed before the article is finished, so that the means of identification are 50 thereafter lost. In this invention the heretofore mentioned objections, and others, are eliminated, and all of the advantages of a symbol or trade-mark are preserved. This is accomplished by 55 providing the pressure face of one or more of the dies 42 with an impression face 39, shown in Figure 12 as diamond shaped. Obviously any

other design may be used equally as well, the shape disclosed being merely for the purpose of illustration. The impression face 39 leaves a corresponding permanent impression in the flat face of the article as the die 42 is withdrawn therefrom. This result is accomplished without the aid or addition of additional parts or operations. An impression upon a side face of the article, as produced in this invention, is not unsightly and does not destroy the neat and 10 pleasing appearance of the article. Neither does it interfere with the grip of the article by a wrench or the like.

15 The above disclosure is given merely as one embodiment of the present invention, which is not to be considered as limiting the invention, the scope thereof being determined by an understanding of the present disclosure as one embodiment thereof and as particularly pointed out in the appended claims.

20 What I claim is:

1. The method of making by a cold process articles having a polygonal cross section, which resides in shaping a substantially cylindrical blank so that at one end it will have a substantially domed surface of solid cylindrical cross section throughout and then applying axial pressure to one end face only thereof, whereby the height of the blank is reduced and the cylindrical cross sectional area thereof increased to 30 a size that is greater in diameter than the distance across the corners of the finished polygonal article, and then applying pressure around the perimeter thereof, whereby the height of the blank is increased and its then cylindrical cross 35 sectional area reduced and made polygonal in form.

2. The method of making by a cold process articles having a polygonal cross section, which resides in shaping a substantially cylindrical blank so that at one end it will have a substantially domed surface of solid cylindrical cross section throughout and then applying axial pressure to one end face only thereof, whereby the height of the blank is reduced and the cylindrical cross sectional area thereof increased to 40 a size that is greater in diameter than the distance across the corners of the finished polygonal article, and then applying pressure around the perimeter thereof, whereby the height of the blank is increased and its then cylindrical cross sectional area reduced and made polygonal in form, and one or more of the sides of the polygon provided with a distinctive symbol, trade-mark, or the like.
